UNITED STATES PATENT OFFICE.

WILLIAM ANDREW DEWBERRY, OF PEACE, ARKANSAS.

SAWING-MACHINE.

SPECIFICATION forming part of Letters Patent No. 380,386, dated April 3, 1883.

Application filed October 25, 1887. Serial No. 253,331. (No model.)

To all whom it may concern:

Be it known that I, WILLIAM ANDREW DEWBERRY, a citizen of the United States, residing at Peace, in the county of White and 5 State of Arkansas, have invented certain new and useful Improvements in Sawing-Machines; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to improvements in machines for sawing various substances—such as logs, timber, or stone—and has for its object to facilitate the operation and apply the power of the workman in the most advantageous manner. My machine can be made either 20 stationary or portable, though the latter is the preferable form of construction. The machine is capable of being folded into small space for transportation; but when set up for use is 25 strong and well braced. It can obviously be driven by hand or by horse power, water or steam.

My invention consists in certain combinations and arrangements of parts hereinafter 30 described, and especially designated in the claims.

Referring to the accompanying drawings, Figure 1 is a perspective view of my machine set up for operating. Fig. 2 is a side elevation; Fig. 3, a detail of construction.

35 The same letters refer to corresponding parts in all the views.

The axle A, wheels B B, and tongue C are of the usual construction. On the axle are 40 erected two posts, D D, united by a cross-piece, E. From one of the posts projects an arm, F, composed of two parts hinged together at f. A pair of staples, f', and a bolt, F', hold the two parts of the arm F rigidly in 45 line. The outer end of the arm is provided with a series of holes, f'', to receive the tenons on the upper ends of the supporting posts or legs G G'. A bar, H, secured to the leg G, passes through a mortise in the leg G', and by 50 means of a pin, h, thrust through a hole in the leg G and engaging one of a series of holes in the bar H, the legs may be adjusted

to any desired distance apart. A diagonal brace, I, runs from the outer end of arm F to the farther end of the cross-piece E. This 55 brace is provided with a hinge, i, as shown.

In the posts D D are journaled three shafts, J, K, and L. The upper shaft, J, may be provided with a crank, J', and carries a gear-wheel, M, engaging with a pinion, N, on the 60 shaft K. On the outer end of shaft K is a fly-wheel, O, which may serve as a belt-pulley in case the machine is driven by a steam-engine or other motor, as indicated by the dotted lines in Fig. 2. This shaft K also carries a 65 gear-wheel, P, engaging with a pinion, Q, on shaft L, on the outer end of which is a crank-disk, R, provided with several holes, r, at different distances from the shaft. A suitable wrist-pin is inserted in one of these holes, its 70 position being determined by the amount of drag or travel to be imparted to the saw S, which is connected with the wrist-pin by a pitman, T. By means of this train of gearing a rapid reciprocating motion can be given to 75 the saw with a corresponding slow revolution of the crank J'. The saw may, if desired, run through guides attached to the legs G G', as indicated by dotted lines in Fig. 1, or through 80 slots in the legs themselves.

Since the pitman T is united to the saw by a loose joint, it is necessary to provide some support for these parts to keep them in line as nearly as possible. I attach to the pitman, 85 near the saw, a rod, U, which is suspended from a lever, V, suitably fulcrumed in a forked upright, W, removably secured upon the arm F, in which is formed a slot, f'', for the passage of the rod U. By means of the lever the rod can be lifted or dropped to raise or lower 90 the pitman, according to the size of the log to be operated upon. This lever V is operated by a cord, X, which is attached to the lever and is wound upon a drum, Y, secured upon a short shaft, Z, mounted in suitable bearings 95 on the post D. At one end of the drum Y is a set of cogs, y, with which a sliding latch, Y', engages when it is desired to lock the drum after winding up or unwinding a certain portion of the cord X. The drum may be turned 100 by a crank, Z', or by a belt, a, running over a pulley, b, on the shaft J, and a loose pulley, c, on shaft Z.

By means of a bolt, d, sliding in a casing se-

cured to the shaft and engaging with a recess, *e*, in the pulley, the pulley may be locked to the shaft. A spring, *g*, pressing against a pin, *d'*, projecting from the bolt *d*, normally retains 5 the bolt out of engagement with the pulley. After the bolt has been pushed into the recess *e* to lock the pulley to the shaft, the bolt is turned on its axis, carrying the pin *d'* into a notch in the casing and retaining the bolt in 10 that position. When the pulley *c* is thus locked to the shaft *Z*, the shaft and the drum can be revolved by the crank *J'*, raising or lowering the saw to any desired extent.

Hinged to the back of the axle *A* is a table 15 or platform, *k*, upon which the workman stands while operating the crank *J'*. The legs of this platform are hinged to it, as shown, and it is provided with an eye, *l*, to engage with a hook (not shown) on the post *D*, whereby it is 20 held up out of the way when the machine is to be moved, the other parts of the machine being stowed away in the following manner: The saw is detached from the pitman *T* and slid into the loops 1 2 on the back of posts *D D*.

25 Rod *U* is detached from the pitman and lever *V* from the forked upright *W*, which is then removed from arm *F* and placed in the box *m*, suspended from the axle. The brace *I* is detached from the arm *F*, folded on its hinge *i*, 30 and then laid along the cross-piece *E*, where it is secured by the hook 3 and staple 4. The legs *G G'* are removed from the holes *f''* and hung from the cross-piece *E* by means of the hooks 5 and eyes 6. The bolt *F'* being with- 35 drawn from the staples *f'*, the other end of the arm *F* is folded back and hooked to the eye 7. Pitman *T* is then hung upon the hook 8 by the eye 9. Lever *V* is laid upon the folded arm *F* and the end of rod *U* brought back and 40 hooked upon the hook 10 by the eye 11. The various bolts and screws which may have been removed in separating the parts are placed in the box *m*. The machine is then in compact form for transportation.

45 Having described my invention, what I claim, and desire to secure by Letters Patent, is—

1. In a portable sawing-machine, the com-

bination, with the frame, of a hinged arm, *F*, and the legs *G G'*, arranged parallel with each other and removably attached to the arm *F*, 50 substantially as described.

2. The combination, with posts *D D* and cross-piece *E*, of the arm *F*, fastened to one of the posts *D* and composed of two parts hinged together and provided with the staples *f'* and bolt *F'*, the removable and adjustable legs *G G'*, attached to the outer portion of the arm *F* and having bar *H*, fastened to one of the legs and adjustably secured to the other, and the brace *I*, extending from the arm *F* to the cross-piece 55 *E*, substantially as described.

3. The combination, with the posts *D D* and the cross-piece *E*, having hooks 3 and 5 and staple 4, of the hinged arm *F*, having hook and eye 7, the hinged brace *I*, and the removable legs *G G'*, having bar *H* and eyes 6, substantially as 65 described.

4. In a portable sawing-machine, the combination, with the driving-shaft *J*, having pulley *b*, of the shaft *Z*, having loose pulley *c*, the belt *a*, connecting the two pulleys, the bolt *d*, secured to the shaft *Z* and adapted to engage with the pulley *c*, the drum *Y*, mounted on the shaft *Z*, the cord *X*, wound upon the drum, the lever *V*, to one end of which the cord *X* is attached, and the rod *U*, attached to the other end of the lever and connected with the saw, 75 substantially as described.

5. The combination, with axle *A*, having box *m*, of posts *D D*, having loops 1 and 2, eye 7, and 80 hooks 8 and 10, the cross-piece *E*, having hooks 3 and 5 and staple 4, the hinged arm *F*, having a hook, and hinged brace *I*, the removable legs *G G'*, having bar *H* and eyes 6, the saw *S*, the crank-disk *R*, the pitman *T*, having eye 9, lever *V*, and rod *U*, having eye 11, and, the removable upright *W*, substantially as described. 85

In testimony whereof I affix my signature in presence of two witnesses.

WILLIAM ANDREW DEWBERRY.
